DARWIN ALMY, OF TIVERTON FOUR CORNERS, RHODE ISLAND.

Letters Patent No. 64,619, dated May 14, 1867.

PLOUGHS.

The Schedule referred to in these Letters Patent and making part of the same.

TO ALL WHOM IT MAY CONCERN:

Be it known that I, DARWIN ALMY, of Tiverton, in the county of Newport, and State of Rhode Island, have invented a new and useful improvement in Ploughs; and I do hereby declare that the following is a full, clear, and exact description thereof, which will enable others skilled in the art to make and use the same, reference being had to the accompanying drawings, forming part of this specification.

The drawing represents a land-side view of a plough with my improved regulating wheel attached.

This invention consists in a guide or regulating wheel, which is designed, with its connections, for attaching to any common plough, and detaching when desirable, as hereinafter described. By means of this simple device the depth of the furrow may be regulated and the plough steadied and made more uniform in its operation. It also gives the ploughman greater control over the plough, and enables him to work nearer stone walls and fences and in the corners of a lot, so that there shall be less waste land left than usual in ploughing a field.

A is the land-side of an ordinary cast-iron mould-board plough, stocked as usual, B the beam, and C a handle. A wooden lever, D, is pivoted at the lower end to the land-side at α , placed on the inside, and is connected with an iron rod, b, that runs forward on the inner side of the beam nearly to its fore end, where the end is pivoted at the joint of two short straight links c c', connected together at one end, on the same pivot d with the rod b. The link c is pivoted at one end to the plough-beam B, and the link c' is pivoted at one end on the axle e of the wheel E, which may be made of cast iron. A single straight link or connecting-rod g is also pivoted, one end on the axle e and the other by the bolt h on the plough-beam B. It will be seen that the movement of the lever D will operate the wheel E, by its connections, to raise or lower it at pleasure, and thus it may be set at any point for regulating the depth of penetration of the plough in mellow ground, while it is easily taken off for ploughing stony ground, where it does not work advantageously.

Having described my invention, I claim as new, and desire to secure by Letters Patent—

The arrangement of the lever D, the rod b, and the links c c' and g connected with the guide-wheel E for regulating the depth of the furrow of a plough operating as herein described.

DARWIN ALMY.
